CLAIM

USPC **D15/29**; D15/28

The ornamental design for a coupler for a ground engaging machine implement, as shown and described.

(58) **Field of Classification Search**

DESCRIPTION

USPC D15/11, 28, 29; 37/456, 452, 450, 446, 37/454, 449, 453, 455, 903; 403/379.5, 403/DIG. 1; 111/152; 172/724, 730, 766, 172/770, 771, 721, 713, 699, 772
CPC Y10T 29/49826; Y10T 403/589; Y10T 403/7018; Y10T 403/7075; E02F 9/28; E02F 9/2825; E02F 9/2833; E02F 9/2866; E02F 9/2858; E02F 9/2808; E02F 9/2841

See application file for complete search history.

(56) **References Cited**

FIG. 1 is an upper, right-side perspective view of a coupler for a ground engaging machine implement showing my new design

U.S. PATENT DOCUMENTS

FIG. 2 is a front view thereof;

1,220,186 A	3/1917	Chambers
1,384,701 A	7/1921	McMonegal
1,571,782 A	2/1926	Andrews
1,856,930 A	5/1932	Robin
2,427,651 A	9/1947	Baer

FIG. 3 is a rear view thereof;

FIG. 4 is a right side view thereof, the left side view being a mirror image thereof;

FIG. 5 is a top view thereof;

FIG. 6 is a bottom view thereof; and,

FIG. 7 is a bottom, right side perspective view thereof.

The relatively light and dark shade lines indicate contour and not surface decoration.

The dashed broken lines are for the purpose of illustrating

portions of the coupler of a ground engaging machine

implement and form no part of the claimed design.
